COMBINED PRAYER CABINET AND BENCH UNIT

Elaine Berg, Chicago, Ill.
(Box 220, Crystal City, Manitoba, Canada)

Filed Nov. 15, 1961, Ser. No. 67,536

Term of patent 14 years

(CL D29—23)

The essential features of the design reside in the portions shown in solid lines on the drawing.

I claim:

The ornamental design for a combined prayer cabinet and bench unit, as shown and described.
